(57) **CLAIM**

The ornamental design for a connector for containers, as shown and described.

DESCRIPTION

FIG. 1 is a perspective view of a connector for containers; FIG. 2 is a front view thereof; FIG. 3 is a rear view thereof; FIG. 4 is a right side view thereof; FIG. 5 is a left side view thereof; FIG. 6 is a top view thereof; and, FIG. 7 is a bottom view thereof.

In the drawings, the broken lines show portions of a connector for containers that form no part of the claim.
